PHOTOGRAPHIC DEVELOPING MACHINE

Anthony Ludwig, Washington, D. C.

Application July 5, 1945, Serial No. 603,310

14 Claims. (Cl. 95—89)

1

This invention relates to photographic processing machines and particularly to those machines wherein a plurality of sensitized objects are progressively and simultaneously put through several steps to develop, treat, bleach, dye, fix, wash, dry or otherwise process sensitized material.

In developing machines, it is desirable to have provision for varying the time of treatment of the film during one step of the complete treatment while the time or time of other steps may be permitted to remain the same or be also relatively changed. This need is brought about by the desirability of using the same developing machine for entirely different processes or for example with developers of different speeds under varying conditions of the trade.

The primary object of the invention is the provision of an improved photographic developing machine.

Another object of the invention is the provision of an improved photographic developing machine wherein the front and one side of the machine are clear of obstructions to permit full opportunity for inspection and operation of the machine.

Still another object of the invention is the provision of an improved photographic developing machine wherein the transfer mechanism is entirely supported at the far side of the machine, thus reducing this part of the construction to a minimum and thereby reducing costs of construction and maintenance to a minimum.

A further object of the invention is the provision of an improved photographic developing machine wherein independent feeding devices for moving the sensitized objects from one end of a tank to another end may be so adjusted as to vary the time in any one tank, independently of and without changing the time of treatment in another tank.

A still further object of the invention is the provision of an improved photographic developing machine wherein sensitized objects are successively passed through tanks for treatment in the various steps of the process and wherein incremental movements are given the objects being treated, the length of the increments of movement between the point of deposit in one tank and the point where the object is to be lifted from the tank, may be varied without varying the time of treatment or the length of incremental movements in another tank.

A still further object of the invention is the provision of an improved photographic developing machine wherein there are a plurality of

2

tanks for carrying out the various steps in the process and wherein a single mechanism is provided for moving the sensitized objects through the respective tanks, and separate adjustable means for independently determining the time the objects will remain in any particular tank.

Another and still further object of the invention is the provision of an improved photographic developing machine wherein are a plurality of tanks having a delivery of liquid from one tank to the other.

Another and still further object of the invention is the provision of an improved photographic developing machine wherein are a plurality of water or washing tanks, one of the tanks having a water level higher than the water level of the other and having an overflow delivery from the higher level to the lower level and in a direction opposed to the progress of the sensitized objects through the machine.

Another and still further object of the invention is the provision of an improved photographic machine wherein sensitized objects are successively passed through tanks for treatment in the various steps of the process and wherein incremental movements are given the objects being treated, the length of increments of movement between the point of deposit in one tank and the point where the object is to be lifted from the tank, may be varied without varying the time of treatment or the length of incremental movements in another tank and having an initial increment adjusting means and an independent but coacting means for giving additional readily settable and predetermined increments for increasing and decreasing the lengths thereof, at will, and returning to another setting, as desired.

Other and further objects of the invention will be apparent to those skilled in the art from a reading of the complete specification.

Referring to the drawing wherein is illustrated a preferred embodiment of the invention.

Fig. 1 is a side view of the invention.

Fig. 2 is a front view.

Fig. 3 is a view of the developing machine from the rear with the dryer omitted.

Fig. 4 is a detail view from the line 4—4 of Fig. 1.

Fig. 5 is a top plan view of the feed-control device shown in the upper left corner of Fig. 1.

Fig. 6 is a front to rear detail view of the feed-control device of Fig. 5.

Fig. 7 is an enlarged view of the structure shown in Figs. 5, 6 and 7 but shown in the position as illustrated in Fig. 1.

Fig. 8 is a diagrammatic view of the power mechanism of the machine.

Figs. 9 and 10 are cross sectional views on the lines 9-9 and 10-10 of Fig. 8.

Fig. 11 is a side view of the feed control device which is particularly useful in control of the progress through the developer tank.

Fig. 12 is a cross sectional view on the line 12-12 of Fig. 11.

Fig. 13 is an enlarged side view of the feed control device illustrated at the sides of tank 20^b, 20^c and 20^e, in Fig. 1.

Fig. 14 is a cross section on the lines 14-14 of Fig. 13.

Fig. 15 is a rear view of the machine, including the dryer frame.

Fig. 16 is a detail view of the transfer bar.

In the drawing and throughout the specification, similar reference characters refer to the same or similar parts.

The numeral 20 designates generally a row of tanks which in the illustrated embodiment is shown as for the usual and well-known method of developing and fixing of sensitized objects such as film or dry plates. In Fig. 1, the developer tank is designated as 20^a and is the first tank into which the sensitized objects are placed. At the rear of this developer tank 20^a is the acid or "short stop" tank 20^b into which the sensitized objects are placed after spending the predetermined time in the developer tank.

After leaving the tank 20^b, the sensitized objects are lowered into the hypo tank 20^c. This tank 20^c, in practice, performs the greater part of the fixation step, after which the sensitized object is transferred to the tank 20^d which normally, having to do less fixing, contains a fresher hypo solution. Even though the solution in the tank 20^c is nearly exhausted, the passage through the second and fresher hypo solution in tank 20^d, insures complete fixation.

Still further to the rear of the hypo tank 20^d are two water tanks 20^e and 20^f. These tanks 20^e and 20^f, have a water passage connection therebetween and in the illustrated embodiment, this connection takes the form of a cascade from the rear tank 20^f to the adjacent forward tank 20^e. In order to provide a head for the water flow from the tank 20^f to the tank 20^e, the water level of the tank 20^f, is slightly higher than that of the tank 20^e, with an overflow spillway between the tanks.

In carrying out this invention, there are provided two coordinated mechanisms which, as illustrated, are operated from the same source of power. These mechanisms are (1) means for transferring the sensitized objects from one tank to another and to the dryer, and (2) mechanism for feeding the sensitized objects along from the position of deposit within any particular tank or on the dryer to a position where it may be removed therefrom and redeposited in the next tank for the next step of the process. The feeding means acts also as an agitator to insure uniform action throughout the time it is in the tank. The feeding means is provided with a coating device by which the progress through the tank is varied to provide for controlled movement to provide a predetermined length of time for any or all steps.

The mechanism for transferring the sensitized objects from one tank to another will first be described and for the purpose of illustration and example, the ordinary process of developing fix-

ing and washing photographic roll films will be used.

As the film comes to the laboratory for development, it is on its roll and either in an envelop having the name or number of the owner or is otherwise provided with a means of identification.

Racks 21 having a substantially rectangular cross section are provided with a series of strip clips 21^a for attaching the unrolled films while being processed and if desired envelop clips 21^b may be provided above the strip clips on the rack 21 for carrying the envelop during the operation. In addition there is provided a roll clip 21^c.

These racks which are usually placed in a portable frame adjacent the developer tank may be prepared in the daylight by removing the film roll from the envelop, placing the envelope or other identification means in the clip 21^b and the roll in the clip 21^c to which the clip 21^b corresponds. With a frame full of such racks, and in the developing room, the operator simply removes the rolls from the clips 21^c removes the film strip from the roll and secures it in a vertical position at one end by the clip 21^a. A weighted clip is secured to the bottom of the strip. In this way, the film strip always stays with its envelop and no normal opportunity for confusion is present.

When the operator is ready to start a film strip rack 21 on its way through the developing machine, it is placed upon the arms 22, which are supported by two standards 23 at the front corners of the developer tank 20^a. Guides 22^a guide the racks back to the stops 22^b, against which a rack 21 must rest in order to be picked up by the transfer mechanism which will now be described.

In order to have the transfer mechanism operate efficiently, it must be well supported. However, at the same time, it is always most convenient not to have operating parts in position to interfere with the inspection at one side of the tanks. To provide for these advantages and to reduce the amount of mechanism, I provide support for both sides of the transfer mechanism at one side of the tanks.

Two columns 24, 25 are provided respectively at the front and rear of the developing machine and on the same side thereof. At the top of these columns are sprocket wheels 26, 27 which support the upper portions of the transfer chains 28 and 29. These chains are operatively connected together as will be presently described. The lower portions of these chains are supported by other sprockets suitably mounted on the columns 24, 25. These sprockets and their drive mechanism will be later described.

Secured to the chains 28, 29, at corresponding points are the ends of an inner supporting transfer rail 30. As the chains 28, 29 operate in unison, the rail 30 being attached, is always maintained in a horizontal position as it is moved bodily by the chains 28, 29. Extending upwardly from the rail 30 are two pairs of uprights 31. Connecting the upper ends of each pair of uprights 31 are stabilizing strips 32. Passing on the inside of each of the stabilizing strips 32 and on the opposite side of the inner rail 30, is a slide bar 33. These slide bars 33 are secured at their upper ends to the column-connecting member 33^b and at their lower ends to similar bars also supported by the columns 24 and 25.

Extending transversely of the tanks and secured to the uprights 31 are cross frame members 33^a which are supported from the uprights 31 by brackets 33^b. At the outer ends of the transverse

frame members 33^a are bracket members 33^c from which depending members 34 carry at their lower ends, the outer transfer rail 35. Diagonal braces 36 are provided between tops of the depending members 34 to the bottoms of adjacent depending members 34. Cross braces 34^a are secured between adjacent inner members 33^a to complete the truss construction.

Strap members 37 connect the upper ends of the upright members 31 with the depending members 34. Together the parts 31, 33^a and 37 with their braces 34^a and 36, provide a cantilever construction for supporting the outer rail 35, through the depending members 34.

It has been noted that the stabilizing strips 32 are on the outside of the respective slide bars 33 and the inner transfer bars 30 are on the inside of the same bars 33. From this construction, it is clear that with the weight of the cantilever construction overhanging the tanks, the strips 32 and the inner transfer bar 30 will always be against the slide bars 33. As wear plates and to reduce friction there is provided on each inner transfer bar 30, a strip 30^a for each slide bar 33.

On the inner sides, adjacent the tank edges, of the inner and outer rails 30, 35, are lifting brackets 38. These lifting brackets 38 are spaced apart such a distance that the ends of the rack bars 21 will just rest in the brackets 38 to permit the latter to raise the bars with the attached film strips. In this connection, it is to be noted that the brackets 38 are so spaced along the inner and outer bars 30, 35, that when the bars 30, 35 are on their upward movement, to be described, each pair of brackets 38 will be in position to lift one rack bar 21 which may be against the stops 22^b to place its film strips in the front end of the developer tank. Also, the brackets 38 will be in positions to lift the racks 21 at the rearmost positions of the respective tanks, to deliver the film strips to the next tank for further processing.

The adjacent tank edges are provided with inverted trough members 39 having their edges at the tank edges to return dripping solution to the respective tanks as the film strips are lifted from one tank to the next. Adjacent the front of each of the sides of each tank is a ramp 40 in position to receive the rack bar 21 as the latter is deposited by the transfer brackets 38.

The purpose of this ramp construction is to advance the film rack a distance greater than the feeding mechanism, to be described, would normally advance the strips. This action provides sufficient space for the film strips of the next deposited rack to enter the tank without being interfered with by the front edge of the tank into which it is being lowered.

At the sides of the tank are main feeder bars 41 which are supported by links 42. These links 42 are pivotally connected to the bars 41 at 42^a, the lower ends of the links 42 are pivotally mounted at 42^b on crank wheels 43^x. Secondary or auxiliary feeder bars 43 are mounted above the main feeder bars 41 and are supported above the latter by parallel links 44, which are pivoted at their respective ends to the main feeder bars and the secondary feeder bars. The last or rearmost auxiliary feeder bars 43^a are of slightly different construction, the rear lifting edge 43^b being higher than the lifting edge 43^c. These feeder bars 43^a by their lifting edges 43^b, 43^c coat with the upper edges of the tanks 20^e and 20^f respectively.

Brackets 45 limit the movement of the parallel links 44 in a forward direction and springs 46 are provided and have their ends secured to the links

44 and the feeder bars 41. The brackets 45 are mounted on the bars 41 and are provided with a contact button 45^a against which the forward link 44 of each auxiliary feeder bar 43 rests when held in the forward position by the spring 46.

The crank disks 43^x revolve in unison in the directions of the arrows and lift the main feeder bars 41 and lower them by the coaction of the links 42. It is to be noted that by the relative 10 positions of the parts, the bars 41 always have a tendency to be thrown to the right, as illustrated in Fig. 1, when they are being raised.

At the rear of each bar 41 and in contact with its end, is a cam 48, mounted on a shaft which 15 rotates in unison with the crank disk 43^x adjacent thereto. The shafts which support the cam 48 and the crank disk 43^x carry sprocket wheels of the same size which are caused to rotate in unison by the chain 49.

20 A spring 50 is provided with one end secured to the tank casing and the other end to the main feeder bar 41. This spring normally holds the bar 41 against the cam 48. It will be observed that the combined action of the crank disks 43^x with the links 42 and the cam 48 will give the bar 41 a movement toward the right in Fig. 1, when the bar 41 is in its lower position and to the left when it is in its upper position.

25 Since the bars 41 carry the auxiliary bars 43, 43^a, it follows that these bars 43, 43^a follow the same movement. The upper edges of the auxiliary bars 43, 43^a are of a height such that when in the low position, they will be below the upper edges of their respective tanks and when in 30 their upper positions these same upper edges of the auxiliary bars 43, 43^a will be above the upper edges of their corresponding respective tanks. In this manner when the racks 21 are in position 35 on the tops of the respective tanks, they will be 40 continually fed to the rear.

At the rear of the developing and washing tanks is a drying device which operates to dry the sensitized surfaces after the washing step. In the illustration, for the sake of clearness, the usual light trap box with its coating curtains and the well-known infra-red lamps, for drying, have been omitted.

The drying apparatus comprises a frame 50 which is supported by the floor and has at its top 50 a supporting rail 51 which is here illustrated as a tubular member which extends forward far enough to be in position to receive the racks 21 as they are delivered to the drying apparatus after being processed in the tank 20^f.

55 Mounted to oscillate in the bottom of the frame 50 are shafts 52. These shafts carry at their ends, double crank plates 53. These crank plates are arranged in alignment and are connected by connecting rods 54 so that they move in unison.

60 Forward of the crank plates 53 on one side of the frame is a pivoted operating lever 55 which is pivoted at its lower end to a connecting rod 56 which latter is similar in construction to the rods 54 and has its lower end connected to the 65 same pivot as the forward end of the forward rod 54 on the crank plate 53. From this it is clear that oscillation of the lever 55 will oscillate the crank plates 54. The upper end of the lever 55 is pivotally connected to a rod 56^a, the other 70 end of which is connected to a crank plate 57 of a shaft 58. The shaft 58 carries a sprocket 57^a which is driven by a chain 59. This chain 59 is in turn, driven by a sprocket 148^a carried by the shaft 148 which drives the crank plate 53 at 75 the rear of the tank 20^f.

Also mounted on the shaft 58 are sprockets 57^b carrying the chains 60 which drive sprockets 61.

The short shafts 62 carry the sprockets 61 and are pivotally mounted in the upper end of the frame 50. Also mounted on and to rotate with each of the short shafts 62 is a cam 63. These cams 63 engage swinging levers 64 which are fulcrumed at 65 on the frame 50, for a purpose to be presently described.

Pivots connected to each of the crank plates 53, is the lower end of a lifting rod 67. The upper ends of these lifting rods 67 are connected to a feeding bar 68 which is supported in the frame 50 in such a way that it may be carried by the lifting rods 67 as the latter are moved up and down and may slide longitudinally in the slots 59^a at the top of the frame 50. See Fig. 6.

As the shaft 58 rotates, the rod 56^a, lever 55 and rod 56 will cause oscillation of all of the crank plates 53. Since the lifting rods 67 are mounted on the plates 53 at about 90° from the pivots 54^a, it follows that the oscillation of the plates 53 will alternately raise and lower the lifting rods 67.

Secured to and adjacent the top of the lever 64 is a plate 71 which engages a small block 72 on the feeding bar 68.

As the shaft 62 rotates, driving the cam 63, it follows that the latter, against the side of the swinging lever 64 will cause the latter to oscillate and move the upper end of the lever against the block 72. This in turn moves the feeding bar 68 longitudinally. A spring 73 connected at one end to the frame 50 and at its other end to the feeding bar 68, tends to force the latter forwardly against the action of the cam 63.

From the above description, it is clear that the cam 63, the lever 64, the block 72 and the spring 73, give the feeding bar 68 a longitudinal movement which is repeated and reversed with each revolution of the shaft 62. It is equally obvious that the oscillation of the shafts 52 with their plates 53 will raise and lower the lifting rods 67 with a resultant raising and lowering of the feeding bars 68. The slots 59^a in which the bars 68 are mounted, permit the vertical bodily movement of the bars 68.

From the combination of the two movements, it is believed obvious that the bars 68 will move forwardly in their low positions below the level of the rail 50 and will then be raised so that the upper edges of the feeding bars 68 are above the level of the tops of the supporting rails 51, and further when raised, the cam 63 and lever 64 will move the bar 68 to the rear to move any racks 21 along toward the rear before the feeding bar 68 is again lowered to an inoperative position.

In the description of the feeding means to move the racks along the tops of the tanks and along the supporting rails 51 of the dryer, nothing has thus far been described for varying the distance moved in each cycle of movement, of the feeding means. In order to provide a construction which will meet the conditions of developers of different speed and for different conditions and processes, there is provided a means for each step of the process for controlling the length of time of treatment in that step by varying the length of step of the movement which thereby varies the time of treatment in that step.

To take care of the varying time of processing in the various steps, I have illustrated three of many different types of devices, any one of which may be used, depending upon the particular

problem to be met and the accuracy of time desired.

For example, at the left in Fig. 1 and in Figs. 5, 6 and 7, is a type which I illustrate with the dryer frame. The feeding bar 68 is provided with an adjustable block 74. The plate 70 which is supported on the frame 50 has an angular lever 75 pivotally mounted thereon as at 75^a. On one end of the lever as at 75^b is pivotally mounted a roller 75^c. This roller is in position to engage the block 74 and stop it in its forward movement under influence of the spring 73 and also permit it to be moved up and down by the rods 67. Mounted on the lever 75 is a leaf spring 75^d which is secured in place at one end by rivets 75^e. At the outer end is a knob 75^f which has on its end a pin which passes through a hole in the lever 75 and is of sufficient length to enter any one of many holes 70^a of the plate 70. These holes 70^a are arranged on the arc of a circle about 75^a as a center. By pulling out on the button 75^f, and swinging the lever 75, the position of the end of movement of the feeding bar 68 is determined, since the block 74 when it engages the roller 75^c, will arrest the movement of the feeding bar 68. And since moving the lower end of the lever 75 to the right in Fig. 1, moves the roller 75^c to the left and thereby shortening the movement of the bar 68 in one cycle, such movement of the lever 75 slows the progress of the drying racks along the rails 51, thereby lengthening the drying process. On the other hand, moving the lower end of the lever toward the left and securing it in position by an opening 70^a, lengthens the increment of movement of the racks 21 and shortens the time of travel to the rear end of the rails 51.

Referring now to Figs. 1, 11 and 12, the segment plate 80, is secured to the side of the frame, as illustrated, in line with the end of an auxiliary feeding rail 43. The plate 80 is provided with guides 81 in which is a slide 82. This slide 82 moves along the guides 81 and is provided with a slot 82^a. A knob 83 is provided with a screw which passes through the slot 82^a and engages a threaded hole in the segment plate 80. By tightening the screw of the knob 83, the slide 82 is prevented from moving in its guides 81. The rearward face of the slide 82 is in position to be engaged by the end of the auxiliary feed bar 43. An adjusting screw 84 having a lock-nut 85 is secured in the end of the slide member 82. Pivotally mounted on the plate 80 is a rock cam shaft 86 to which are secured a cam 87 and an operating handle 88. A locking pin 88^a is secured to a spring 89 which spring is secured in place by screws 90 on the handle 88. A releasing knob 91 is secured at the end of the spring 89 and is used to bend the spring 89 and withdraw the locking pin from locking engagement with the holes 80^a in the plate 80 when a change in adjustment is desired.

As already stated, if the knob 81 is pulled out bending the spring 89, the pin 88^a will disengage from the hole 80^a. Then if the operating handle 88 is swung about the axis of the shaft 86, the cam 87 will press on the head of the adjusting screw 84. If the screw knob 83 is released, the operating handle 88 may be swung to the desired adjustment. In order to secure the desired close adjustment between those afforded by the openings 80^a, the screw 84 with its lock nut 85 is used. After any adjustment is made, the screw knob 83 is tightened.

In using either of the forms just described, the operative has knowledge of which setting will

produce the results which he desires. He thus is able to, at once, change from any speed of advance to any other desired speed by a resetting of the control device.

On Fig. 1, Figs. 13 and 14 is illustrated a third progress control device which is especially adapted for use where quick changes in speed progress of the sensitized object through any particular step of the process is not essential. In this form, the plate 92 is secured to the side of the machine. A slide 93 operates in guides 94 as the slide 82 operates in the guides 81, already described. The construction of the tightening screw knob 95 is similar to the knob screw 83 and operates in a similar manner. A bearing 96 is provided on the plate 92 and in this bearing the knurl-headed screw 97 is mounted to turn. A pinned collar 98 holds the screw 97 in its bearing. The end of the screw 97 is threaded in the slide 93. When the knob screw 95 is loosened and the knurled head of the screw 97 is turned, the slide 93 is moved back and forth at will and is again locked in place by the knob screw 95. The end of the slide 93 is in position to be engaged by the end of the auxiliary feeding bar 43 or 43^a and to control the length of stroke of the auxiliary feeding bar.

The principle upon which all three of these control devices operate is the same. By limiting the movement of the auxiliary feeding bar or the feeding bar in the case of the dryer illustrated, the length of the increment of movement in the speed progress of the feeding bar and the racks 21, moved thereby, is controlled.

The power driving mechanism which operates the transfer and feed mechanisms will now be described.

A motor 100 drives a belt 101 which in turn, drives a pulley 102. This pulley 102 is mounted on a shaft 103 which drives a worm gear unit 104. The worm gear unit 104 has a short shaft 104^a upon which is mounted a gear 105. The gear 105 meshes with a gear 106 which is mounted on the shaft 107. This shaft 107 extends from one end of the machine to the other and connects the gearing which operates the chains 28 and 29, which gearing will now be described.

As already described, the chains 28 and 29 are supported near the tops of their respective towers or columns 24 and 25, by the sprockets 26 and 27. These sprockets have outer faces substantially parallel with the faces of the columns or towers 24 and 25.

The lower portions of the chains 28, 29 are, in the instant illustration, shown as supported by three sprockets—one driver and two idlers. By having such a construction instead of a single lower supporting sprocket an advantage is, in some cases obtained in that with the construction illustrated, more time is consumed between the time of deposit of a rack and the time of pick-up of the next rack, thus making it possible to use columns 24, 25 of less height and still have the last deposited rack out of the way in time to receive the next one.

At each end of the shaft 107 is a bevel gear, as 108, 109. The gear 108 adjacent the front end drives a bevel gear 110 which is secured together with the sprocket 111 and the spur gear 112 by the bolts 113. This assembly is mounted to rotate on the axle bearing 114. The axle bearing 114 is integral with the plate 115 which is bolted to the housing 24 by the bolts 116.

The bevel gear 110, drives the sprocket 111, over which the chain 28 runs and operates the transfer rails 30 as already described. In addi-

tion to the sprocket wheel 111, the lower portion of the chain 28 is supported by the idlers 118, 118^a, the latter being offset and at substantially the same height as the bevel gear 110 and the sprocket 111. The idler sprockets 118, 118^a are supported in the casing of the column in any suitable manner.

At the rear end of the machine, the bevel gear 109 drives the bevel-sprocket unit 117 having a sprocket 117^a and bevel gear teeth 117^b. This bevel-sprocket unit 117, the sleeve 118^a and the spur gear 119 are bolted together by bolts 120 to form a drive unit journaled on the axle bearing 121. The axle bearing 121 is secured to a plate 122 which is bolted by the bolts 123 to the housing 25 of the rear column. The chain 29 runs on sprocket 117^a and is driven thereby.

At the lower portion of the column housing 25, the chain 29 is supported by the driving sprocket 117^a and the idler sprockets 124, 125 which are similar in construction and function to the idler gears 118 and 118^a.

The power transfer gearing connection from the column or towers 24, 25 to the feeding mechanism will now be described.

Beneath the spur gear 112 of the housing 24 is an idler gear 126 which is suitably mounted on the housing 24 and to mesh with the spur gear 112 and another spur gear 127. This gear 127 is mounted on one end of the shaft 128 which extends through the housing 24 to and across the front of the tank 20^a and has a spur gear 129 in position to engage a similar spur gear 130 which is mounted on the shaft 131.

A sprocket 132 is connected by a chain 133 which drives a sprocket 134. This sprocket 134 is mounted on a shaft 135 which carries at its end the forward crank plates 43 already described.

As the crank plate 43, as viewed in Fig. 1, turns clock-wise, so does the shaft 131 which drives it. The shaft 128, as viewed from the same point, turns counter-clockwise as does the sprocket wheel unit 111 to which it is operatively connected by the spur gear 112 and the idler gear 126.

Similarly in the rear column 25, the spur gear 119 meshes with an idler gear 140 which is suitably mounted within the housing 25, which idler gear 140 meshes with the spur gear 141. The gear 141 is mounted on a shaft 142 which carries a spur gear 143 located at the rear of the tank 20^a.

The spur gear 143 drives a similar spur gear 144 on the shaft 145, in the opposite direction. On the end of the shaft 145 is located the cam 48 already described. Also on the shaft 145 is the sprocket 146 which drives the chain 49 already described. The chain in turn drives the sprocket 147 on the shaft 148.

This shaft 148 carries at its outer ends the crank plates 43^a for driving the rear lifting mechanism of the feeding rail. Also on the shaft 148 is the sprocket 149 which drives the dryer drive chain 59 already described.

Having described the construction and operation of the individual parts of the invention, the operation of the machine as a whole will now be described.

In assembling the parts of the machine, the inner transfer rail 30 is attached to its carriers 28 and 29 so that the rail is horizontal and in such a manner that both ends will travel together under the power operation of the connecting shaft 107.

The tanks are first filled with the appropriate liquid or solution.

If the time of treatment of any particular sensitized surface by the liquid of a particular tank is known, a test of the timing operating mechanism of that tank may be made to determine if it has the correct timing. This may be done by operating the machine and putting the rack through the operation with no sensitized object attached. The time between deposit above the tank and the pick-up by the brackets 38 having been found to be too slow or too fast, the devices illustrated in Figs. 5, 6, 7, 11, 12, 13 and 14 are adjusted as already described. This is repeated for all tanks or for the dryer where necessary.

In steps of the process where it is necessary to make a quick change from one speed through a tank to another speed, one of the devices illustrated in either Fig. 7 or Fig. 11 would be used.

In the actual operation of the machine, the rack 21 with the sensitized object attached, is placed upon the arms 22, being guided into place against the stops 22^b, by the guides 22^a. These latter contact the two outer clips 21^a to center the rack to be in position for the pick-up by the brackets 38, of the rails 30, 35. As the transfer assembly places the brackets 38 beneath the ends of the rack 21, the latter is lifted high and then lowered to permit the sensitized surface to enter the first tank.

The feeding rails of the feeding mechanism now causes the auxiliary rails 43 and 43^a to move the rack 21 along the top of the tank to its rear where it is again picked up by the brackets 38 appropriate to that tank, and deposited above the next tank or in the last step on the dryer rails 51 where it is fed along to the rear of the dryer frame where it will have been dried and ready for removal.

While an embodiment of the invention has been illustrated and described in detail in connection with one of the usual and well known processes for developing films, it is to be understood that the disclosure is merely illustrative and that the sensitized object may be on the surface of film, glass, paper, wood, china or any other suitable substance; that the invention is adapted for use with the necessary or desirable modifications and changes to other or newer processes of treating sensitized objects as, for example, in color photography; that other modifications and changes may be made without departing from the spirit of the invention and within its scope as claimed.

Having described my invention, what I claim is:

1. A photographic developing machine having a plurality of tanks for treating solutions comprising means for progressively and automatically moving sensitized objects through the solutions of the tanks successively in a step-by-step movement, selective means for predeterminedly adjusting the length of step in the step-by-step movement in one tank independently of the adjustment of the length of the step in the step-by-step movement of sensitized objects in another tank.

2. A photographic developing machine having a plurality of tanks for successively treating sensitized objects, comprising means for each tank for progressively feeding the sensitized objects step-by-step through the tanks when being treated, from one part of a tank to another part, and means for each tank for adjustably determining the length of the step of the step-by-step

movement of objects in one tank independently of the length of the step of the step-by-step movement of objects in another tank.

3. A photographic developing machine having a plurality of tanks for successively treating sensitized objects, comprising a mechanism for moving sensitized objects being treated by step-by-step movement through tanks from end to end successively, and adjustable means for changing the length of the step of the step-by-step movement through one tank independently of the step of the step-by-step movement through another tank.

4. A photographic developing machine having a plurality of tanks for treating solutions, comprising means for moving a sensitized object, when being treated, from one tank to another, a mechanism for moving the object through a tank when being treated, by an up, forward, and downward step-by-step movement from one end of a respective tank to the other end and means for adjustably predetermining individually, the length of the step, and thereby the time of treatment in any tank relative to the time of treatment in another tank.

5. A photographic developing machine having a plurality of tanks for treating solutions, comprising means for moving sensitized objects from one tank to another when being treated, a mechanism for moving a plurality of objects when being treated, by a step-by-step movement through each tank, and means for adjustably predetermining the length of movement of the step in the step-by-step movement in one tank independently of the length of step in another tank, thereby predetermining the length of time of treatment in any tank independently of the length of time of treatment in another tank.

6. A photographic developing machine having a plurality of tanks for treating solutions, comprising means for moving an object when being treated, from one tank to another, means for each tank for moving the object when being treated, by a step-by-step movement from one end of that tank to its other end and adjustable means for, at will, changing the length of step in the movement in one tank independently of and relative to the length of step in the movement in another tank.

7. A photographic developing machine having a plurality of tanks for treating solutions, comprising means for each tank for progressively feeding a sensitized object when being treated, from one part of the tank to another part, a common means adjacent the sides of the tanks for moving the progressive feeding means of the tanks, means for transferring the object being treated from one tank to another and adjustable means individual to its tank and including an object-moving means carried by the common progressive feeding means for predeterminedly varying the time of treatment in one tank relative to the time of treatment in another tank.

8. A photographic developing machine having a plurality of tanks for treating solutions, comprising means adjacent each tank for progressively feeding an object when being treated, from one part of the tank to the opposite part, a common means for lifting the sensitized objects being treated, successively, from one tank to the next tank when the object reaches a point adjacent the end of that tank, and means including an object-moving means on the progressive feeding means for varying the speed of progress

through one tank without changing the speed of progress in the other tank.

9. A photographic developing machine having a plurality of tanks for treating solutions, comprising means for progressively moving an object being treated from one tank to another, and means for causing movement through and adjustably predetermining the time of treatment in one tank without changing the time of treatment in another tank, said predetermining means including a step-by-step movement-causing means for each tank and a variable position stop for each movement-causing means to limit the length of each step in the step-by-step movement, thereby varying the speed of progress through that tank.

10. A photographic developing machine having a plurality of tanks for treating solutions, comprising means for progressively moving objects from one tank to another when being treated, and from one end of one tank to its other end and including a bar movable in a non variable closed path and a plurality of feeding elements carried by the bar, each being individual to its tank, and having a variable path, and means for predeterminedly controlling the variable path of each of the feeding elements to cause its movement into and out of feeding position at variable times, to vary the speed of progress of the sensitized object through the tank, independently of the feeding of the other feeding element.

11. A photographic developing machine having a plurality of tanks for treating solutions, comprising elongated members extending along the sides of the tanks, power means for giving elevational and longitudinal movement alternately to the elongated members in respective closed paths, feeding members for the respective tanks and movably supported on the elongated members and in position to move the objects when carried to their upper positions by the elongated members, and movement-controlling means for varying the time of effective operation of the feeding means, thereby controlling the speed of progress and movement of the sensitized members by the feeding means.

12. A photographic developing machine having a plurality of tanks for treating solutions, comprising a pair of bars mounted at the sides of the tank and extending substantially the combined lengths thereof, means for bodily moving the bars in substantially vertical planes while maintaining their positions substantially horizontally, individual feeding members mounted for longitudinal movement on the bars and of substantially the lengths of their respective tanks, the upper portions being slightly higher than and parallel to the tank edges when in their upper positions, object carriers of a length to be moved by the feeding members when moved to their upper positions by the bars, means individual to each tank for independently varying the length of effective feeding movement of the feeding members and means for bodily lifting and moving the object carriers from one tank to another.

13. A photographic developing machine having a plurality of tanks for treating solutions, comprising a pair of bars mounted at the sides of the tank and extending substantially the combined lengths thereof, means for bodily moving the bars in substantially vertical planes while main-

taining their positions substantially horizontally, individual feeding members swingingly mounted on the bars and of substantially the lengths of their respective tanks, the upper portions being slightly higher than and parallel to the tank edges when in their upper positions, object carriers of a length to be moved by the feeding members when moved to their upper positions by the bars, means individual to each tank for independently varying the length of effective feeding movement of the feeding members and means for bodily lifting and moving the object carriers from one tank to another.

14. A photographic developing machine having a plurality of tanks for treating solutions, comprising a pair of bars mounted at the sides of the tanks and extending substantially the combined lengths thereof, means for bodily moving the bars in substantially vertical planes while maintaining them in horizontal positions, individual feeding members mounted for longitudinal movement on the bars and of substantially the lengths of their respective tanks, the upper portions being slightly above and parallel to the tank edges when in their upper positions, object carriers of a length to extend to positions across the tanks and above the feeding members of the respective tanks, to be lifted by the feeding members and moved along the tops of the respective tanks, and means individual to each tank for varying the duration of effective movement of the feeding members to predetermine the speed of progress of the sensitized object through the tank.

ANTHONY LUDWIG.
